CLAIM

I claim the ornamental design for a brake disc, as shown and described.

DESCRIPTION

FIG. 1 is a front, top, right perspective view of a brake disc showing my new design; and,

FIG. 2 is a front elevation view thereof.

The broken line showing is for the purpose of illustrating portions of the brake disc and forms no part of the claimed design.

1 Claim, 2 Drawing Sheets

FIG. 1

FIG. 2
